UNITED STATES PATENT OFFICE.

FRANK G. FEELEY, OF CHICAGO, ILLINOIS, ASSIGNOR TO M. D. KNOWLTON COMPANY,
OF ROCHESTER, NEW YORK, A CORPORATION OF NEW YORK.

CUTTING MECHANISM.

1,138,369.

Specification of Letters Patent.

Patented May 4, 1915.

Application filed August 12, 1913. Serial No. 784,465.

To all whom it may concern:

Be it known that I, FRANK G. FEELEY, a citizen of the United States, and resident of Chicago, in the county of Cook and State 5 of Illinois, have invented certain new and useful Improvements in Cutting Mechanism, of which the following is a specification.

This invention relates to improvements in cutting mechanism, and particularly the cutting mechanism of machines such as slotting machines for slotting cardboard, etc. In machines of this type as ordinarily constructed it is customary to employ a series 10 of cutters or knives and mount these on a suitable support, such as a cutter-bar, in such a manner that the knives will cut in parallel planes to form parallel slots in the material. Ordinarily these cutters or knives are mounted on knife-holders which are secured to the cutter-bar in such a manner that 15 they may be adjusted to different positions in the length of the cutter-bar and secured in such positions for operation. The knife-holders employed are relatively narrow and 20 it has been found that in practice they do not support the knives as rigidly crosswise thereof as is desirable, for which reason the knives are almost invariably worn on the side in such a manner as to indicate that in 25 operation the movable knife strikes on the side as it works up and down and is correspondingly worn on the side, owing to the insufficient support afforded by each relatively narrow knife-holder.

The principal object of the present invention is to provide an extended support for 30 each knife and knife-holder which support will be sufficient to prevent the slight tipping or canting of the knife-holder that takes place when this holder is of the usual 35 relatively narrow type just described.

A further object of the invention is to provide such an extended support for each knife and its knife-holder without increasing 40 the width of any knife-holder and without interfering in any way with the adjustment of the same crosswise of the knives or preventing such holders from being brought 45 into juxtaposition sidewise when it is desired to cut slots very close together in the material being operated upon. The means employed for furnishing an extended support 50 is of course intended to furnish such a support crosswise of each knife and its holder

and in the preferred construction coöperates 55 with the cutter-bar and the knife-holder in such a manner as to assure the maintenance of these parts in a predetermined relation crosswise of the knife-holder, so that no sidewise tipping or canting of the knife and 60 its holder can occur after the holder and the extended support have been properly secured in position on the main support for the knife-holder. In order that each knife-holder and its knife may have a relatively 65 great extended support crosswise of the knife, I employ a series of devices, one for each knife-holder, which devices are disposed in different positions crosswise of the knives and in such a manner that no one of 70 them will interfere with the adjustment or operation of the knife, knife-holder or extended support of any other cutting unit, this result being accomplished in any one of various ways.

75 Other features of the invention not hereinbefore referred to will be hereinafter described and claimed and are illustrated in the accompanying drawings, in which—

Figure 1 is a sectional end elevation of a 80 cutting mechanism embodying upper and lower cutters, cutter-holders and supports, etc., constituting, in this case, part of a slotting machine and embodying my present invention; Fig. 2 is a plan on a smaller scale 85 of a portion of the same with the upper cutter-bar or support removed; Fig. 3 is a view similar to Fig. 1 of a modification of the invention showing another species of the extended support for the upper cutters or 90 knives; Fig. 4 is a plan of the same; Fig. 5 is a view similar to Fig. 3 of the lower portion 95 of the cutting mechanism illustrating a modification embodying an extended support for the lower cutters or knives, and Fig. 6 is a plan of the same.

Similar characters designate like parts in all the figures of the drawings.

Referring first to Figs. 1 and 2, 2 and 3 100 designate respectively upper and lower supports for knife-holders and knives, the upper being the usual cutter-bar or cross-head, while the lower is the bed with ways thereon of a slotting machine. On these supports 2 and 3 are mounted upper and lower knife-holders, designated generally by 4 and 5, respectively, the former being preferably adjustable lengthwise of the cutter-bar 2 and 105

the latter being adjustable similarly lengthwise of the bed 3. Each of the main supports 2 and 3 has the usual inclined or dove-tailed ways, 2' and 3', coöperating with corresponding dove-tailed grooves in the knife-holders 4 and 5. The upper cutters or knives may be of the usual type indicated at 6, and are securely bolted to their respective knife-holders 4; while the lower complementary 10 knives or dies are also of the usual type that is formed by long slots, 7, at the upper edges of the knife-holders 5 in which slots the upper cutters 6 work up and down. The upper and lower cutters are held in place 15 on their respective supports by suitable fastening means which secure the knife-holders 4 and 5 to said supports, said fastening means usually being gibbs, such as 8 and 9, suitably bolted in place.

20 The principal knife-holders 4, it will be noticed, (see Fig. 2) are the usual relatively narrow holders capable of adjustment close up to one another to permit the knives 6 to cut parallel slots relatively close together. 25 For each of these knife-holders extended supports are shown for preventing transverse tipping or canting movement of the 30 holders and knives. These devices are such, in these views, as to provide transverse supports for the knife-holders and knives several times as long as the support afforded by the knife-holder itself. The specific construction shown is one in which a supporting bar, such as 10, is securely fastened to 35 the knife-holder 4, preferably in a transverse groove, 11, in the upper edge thereof, and extends beyond each side of said knife-holder a distance preferably equal to or greater than the entire width of said knife-holder. 40 This bar constitutes a slide-bar intended to move back and forth in a corresponding groove, such as 12, which is cut in the under side of the cutter-bar 2 and in which said slide-bar fits and works, the construction being 45 such that when the clamping means is tightened up said slide-bar will also be secured in place in the groove 12, and all of the parts being tightly held together, will give a substantially rigid support transversely for the knife of the full length of 50 said slide-bar.

Referring to Fig. 2, it will be seen that each of the knife-holders 4 has a slot 11 in the upper side thereof all of these slots being in alinement with one another. The object of this is to permit the knife-holders to be brought into contact if desired while still providing for the support of each knife transversely along the surface of the full 60 length of each slide-bar 10. In Fig. 2 it will be seen that one end of said slide-bar 10 extends into the groove 11 of the next knife-holder. If the knife-holders were in contact with one another this slide-bar would extend 65 into the slot 11 of the third knife-holder.

In addition to providing an extended support the full length of which is available as a supporting means regardless of the adjustment of the knife-holders relatively to one another on the cutter-bar, I also provide 70 means for furnishing an extended support for each of a series of knife-holders without any interference of one knife-holder with the proper adjustment or support of any other. In order to accomplish this result 75 the extended supports are shown as disposed in different positions crosswise of the knives, they being illustrated in the construction shown in Fig. 2 as parallel with one another. Here the second knife-holder 4 has a slide-bar, 10^a, similar to that shown at 10 but parallel therewith and working in slots, 11', of the different knife-holders 4, while the third knife-holder has a slide-bar, 10^b, which works in slots or guide-grooves, 11'', in the 80 knife-holders. It will be evident from Fig. 2 that in any adjusted position of any knife-holder its extended support will be effective to prevent tipping movement crosswise of the knife no matter how close together the 90 knife-holders may be.

Referring to Figs. 3 and 4 a modification of the invention is illustrated in which all of the parts are similar to those just described and are indicated by corresponding 95 reference characters, except that the extended supports coöperating with the upper knife-holders and their cutter-bar are not mounted in guide-grooves between the under side of the cutter-bar and the upper sides of the knife-holders, but are all disposed at one side of the cutter-bar and coöperate with the inclined guide-surface 2' thereof, these extended supports being substantially T-shaped members, 13, 13^a and 13^b, secured respectively to the upper knife-holders 4 near the rear ends thereof. They are so disposed that though their T-heads overlap horizontally interference with one another is avoided by placing them one above another, 100 as clearly shown in Fig. 3, the forward edge of each being inclined at the same angle as the inclined guide-surface 2' of the cutter-bar 2. It will be evident that when the gib 8 is tightened after the knife-holders 4 with 105 their T-shaped extended supports 13, etc., have been adjusted lengthwise of the cutter-bar 2, all of said extended supports will be firmly held to the coacting way of the cutter-bar and will prevent tipping movement of the knives and knife-holders 4, substantially 110 as in the construction shown in Figs. 1 and 2.

Figs. 5 and 6 illustrate a modification of the invention in which is shown the application of the same principle to the lower knife-holders and the knives or dies thereof, corresponding parts being indicated by the same reference characters as in the previous views. The lower knife-holders indicated by 5' are shown here as having bearings, 14, 115 120

14^a and 14^b, extending transversely therefrom near the rear side of the machine, these bearings being disposed in pairs at opposite sides of the knife-holders 5' with their openings in alinement with each other. Each pair of bearings is in a different position from every other in order to avoid interference, these bearings being illustrated as extending from brackets, 16, 16^a and 16^b, depending from the knife-holders 5' in different positions. Through the bearings 14, 14^a and 14^b pass guide-rods, such as 17, 17^a, and 17^b, parallel with one another and securely fastened to the base or bed portion 10 of the machine. It will be evident from Figs. 5 and 6 that in the case of the lower knives also, extended crosswise supports are provided which prevent tipping or canting of the lower knives and their dies 7'; that 15 all of the lower knife-holders may also be adjusted so as to be in contact with one another to cut the slots close together in the material, and that the extended supports for the different knife-holders are so arranged 20 or staggered, substantially as in the case of the upper knife-holders and cutters, that there is no interference of any of these extended supports with any other knife-holder or knife. 25 It will be understood that both the upper and lower knife-holders may be adjusted as usual and simultaneously to corresponding positions lengthwise of the cutter-bar 2 and the bed 3, and then firmly secured in 30 place in the new relation, and that no matter what the positions may be to which the various complementary upper and lower knife-holders and knives are moved, each will always have a relatively long extended 35 support for preventing any tipping or canting of either the upper or the lower knives crosswise of their cutting paths.

What I claim is:

1. In a cutting mechanism, the combination with a cutter-bar, and with a knife-holder carried thereby and disposed transversely thereto, of means coacting with said cutter-bar and knife-holder and extending laterally beyond the latter for furnishing an extended support for said knife-holder and its knife in a direction transverse thereto. 45
2. In a cutting mechanism, the combination with a cutter-bar, and with a knife-holder carried thereby and disposed transversely thereto, of means coacting with said cutter-bar and knife-holder and extending laterally beyond the latter at both sides thereof for furnishing an extended support for said knife-holder and its knife in a direction crosswise of the same. 55
3. In a cutting mechanism, the combination with a cutter-bar, and with a series of knife-holders carried thereby and disposed transversely thereto, of a plurality of de-

vices coacting with said cutter-bar and knife-holders for furnishing extended supports for each of said knife-holders and its knife in a direction crosswise thereof, said devices being disposed in different positions 70 crosswise of the knife-holders.

4. In a cutting mechanism, the combination with a cutter-bar, and with a series of knife-holders carried thereby and disposed transversely thereto, of a plurality of devices coacting with said cutter-bar and knife-holders for furnishing extended supports for each of said knife-holders and its knife in a direction crosswise thereof, said devices being disposed crosswise of the knife-holders at different points in the lengths 75 thereof.

5. In a cutting mechanism, the combination with a cutter-bar having a longitudinal guide-surface, and with a knife-holder 85 carried by said cutter-bar and disposed transversely thereto, of an extended support for said knife-holder projecting from opposite sides thereof, and means for holding said extended support in contact with 90 said guide-surface.

6. In a cutting mechanism, the combination with a cutter-bar having a longitudinal guide-groove, and with a knife-holder carried by the cutter-bar and disposed transversely thereto, of an extended support for 95 said knife-holder projecting from opposite sides thereof and embodying a slide-bar fitting said guide-groove.

7. In a cutting mechanism, the combination with a cutter-bar having a series of parallel longitudinal guide-grooves, and with a series of knife-holders carried by the cutter-bar and disposed transversely thereto, of a plurality of extended supports for 100 said knife-holders each projecting from opposite sides of its knife-holder and each embodying a slide-bar fitting a corresponding 105 guide-groove.

8. In a cutting mechanism, the combination with a cutter-bar, and with a series of knife-holders carried thereby and disposed transversely thereto, of a plurality of devices coacting with said cutter-bar and knife-holders for furnishing extended supports for each of said knife-holders and its knife in a direction crosswise thereof, said devices being disposed crosswise of the knife-holders at different points in the lengths thereof and being movable in paths 110 that overlap the paths of movement of the adjacent knife-holders. 115

9. In a cutting mechanism, the combination with a bed, and with a knife-holder and die carried thereby and disposed transversely thereto, of means coacting with said bed and knife-holder for furnishing an extended support for said knife-holder and die in a direction crosswise thereof. 120

10. In a cutting mechanism, the combina- 125

tion with a bed, and with a series of knife-holders and dies carried thereby and disposed transversely thereto, of a plurality of devices coacting with said bed and knife-holders for furnishing extended supports for each of said knife-holders and dies in a direction crosswise thereof, said devices being disposed in different positions crosswise of the knife-holders.

10 11. In a cutting mechanism, the combination with a fixed bed, and with a cutter-bar movable up and down toward and from said bed, of a pair of knife-holders carried respectively by said bed and cutter-bar, a pair of coacting cutters carried respectively by said knife-holders, and means between the upper knife and the cutter-bar and between the lower knife and the bed for furnishing

extended crosswise supports for said respective knife-holders.

12. In a cutting mechanism, the combination with a cutter-bar having a longitudinal guide-surface, and with a knife-holder carried by said cutter-bar and disposed transversely thereto, of an extended support for 25 said knife-holder projecting from one side thereof, and means for holding said extended support in contact with said guide-surface.

Signed at Chicago, in the county of Cook and State of Illinois, this 7th day of August, 30 A. D. 1913.

FRANK G. FEELEY.
